PRESSURE REGULATOR UNIT FOR UNDER-WATER BREATHING APPARATUS

Earl M. Shugarman, Costa Mesa, Calif., assignor to W. J. Voit Rubber Corp., a corporation of California

Filed Aug. 5, 1964, Ser. No. 81,168

Term of patent 3½ years

(Cl. D83—1)

FIG. 1 is a front perspective of a pressure regulator unit for underwater breathing apparatus;

FIG. 2 is a rear perspective thereof;

FIG. 3 is a plan view as seen from the bottom of FIG. 3.

I claim:

The ornamental design for a pressure regulator unit for underwater breathing apparatus, substantially as shown as described.
